UNITED STATES PATENT OFFICE

95,533

DESIGN FOR A HEATING COIL

Virgil Willis Moray, New York, N. Y.

Application February 4, 1935, Serial No. 55,217

Term of patent 7 years

To all whom it may concern:

Be it known that I, Virgil Willis Moray, a citizen of the United States of America, residing in the Borough of Manhattan, city and State of New York, have invented a new, original, and ornamental Design for Heating Coils, of which the following is a specification, reference being had to

the accompanying drawing, forming part thereof.

The figure is a perspective view of a heating coil, showing my new design.

I claim:

The ornamental design for a heating coil, as shown.

VIRGIL WILLIS MORAY.
